3 Claims

ABSTRACT OF THE DISCLOSURE

A garment curing apparatus for suspending pants or other garments which have been treated with a synthetic resin in such a manner that permanent marking of the garment does not occur during curing of the synthetic resin. Each trouser leg is independently suspended between a pair of rigid prongs and the spacing between the prongs of each pair is adjustable to accommodate varying fabric thicknesses. A plurality of pairs of prongs are affixed to a common assembly which is rotatably attached to a conveyor means to carry garments through the processing steps.

This invention relates to a garment curing apparatus. More particularly, the invention relates to a garment curing apparatus which provides for suspending pants or other garments which have been treated with a synthetic resin in such a manner that permanent marking of the garment does not occur during curing.

With the advent of the "permanent press" treatment of fabric, conventional garment carriers have not been satisfactory. That is, when garments are treated with synthetic resins and thereafter cured in ovens to effect permanent pressing, conventional carriers leave permanent markings in the places where the garment contacts the carrier. For example, folds of garments hung over rods or wires tend to be permanently fixed in the garment upon curing. Similarly, when spring-urged clips or conventional pants hangers are used to suspend garments during curing, the points of contact between the hanger and the garment leave permanent markings on the fabric when cured. It has been proposed to reduce the size of the contact points between hanger and garment. However, after the garments are impregnated with synthetic resin compositions and before curing in the oven, the weight of the garment is relatively heavy. Consequently wrinkles tend to form about the point of contact between the suspension means and the garment suspended. These wrinkles are fixed in the fabric upon curing of the synthetic resin in the oven.

In addition, conventional means for suspending garments, particularly trousers, require a considerable amount of handling and manual contact with the fabric. When the fabric is impregnated with synthetic resin and is not yet cured, extreme care must be taken to avoid unnecessary contact with the uncured fabric.

It has also been proposed to interpose a layer of sponge rubber between the uncured garment and the hanger to reduce the formation of permanent contact lines. However, such holding means does not completely obviate the occurrence of wrinkles and does not reduce the amount of manual handling. Moreover, the sponge rubber on ordinary hangers does not last for a sufficient period of time. The oven temperatures tend to harden the rubber or synthetic resin of the sponge material so that it crumbles and wears off in a short period of time. In addition, when the impregnated garments have a high moisture content, the sponge material tends to pick up a certain amount of resin material from the garment, resulting in an uneven finish.

2

In general, it is an object of this invention to provide a novel garment curing apparatus which will overcome the defects and disadvantages pointed out above in connection with the prior art.

5 A further object of the invention is to provide a garment curing apparatus which permanently impresses only the desired creases and avoids all other wrinkles, folds, and markings.

10 It is another object of the invention to provide a novel garment curing apparatus which is relatively permanent and not subject to excessive wear and deterioration upon repeated heating.

15 An additional object of the invention is to provide a novel apparatus which applies no positive pressure against uncured garments beyond the weight of the garment itself.

20 A further object of the invention is to provide a novel apparatus which is capable of carrying a large number of garments through a series of garment-treating operations with a minimum requirement for manual labor.

25 Further objects and features of the invention will appear from the following description in which the preferred embodiment of the invention has been set forth in detail in conjunction with the accompanying drawing.

Referring to the drawing:

FIG. 1 is a front view of the conveyor means of this invention.

FIG. 2 is a sectional view along line 2—2 of FIG. 1.

FIG. 3 is a sectional view along line 3—3 of FIG. 1.

30 FIG. 4 is a schematic illustration of the garment curing apparatus of this invention.

FIG. 5 is a top view of a portion of the apparatus taken along line 5—5 of FIG. 1.

FIG. 6 is a cross-sectional view along line 6—6 of FIG. 5 showing the suspension of a pant leg in each pair of prongs.

FIG. 7 is a bottom view of the supporting means shown in FIG. 5.

FIG. 8 is a cross-sectional view along line 8—8 of FIG. 5 of the trouser supporting assembly unit.

FIG. 9 is a cross-sectional view along line 9—9 of FIG. 7 illustrating another view of the trouser supporting assembly unit.

FIG. 10 is a cross-sectional view similar to FIG. 6 showing the adjustable feature of the prongs.

FIG. 11 is a cross-sectional view showing an alternative embodiment of the trouser supporting assembly unit.

Referring particularly to FIG. 1, the garment curing apparatus of this invention comprises a suitable conveyor 11, such as one having an endless link chain 12 supported by rollers 28 from the guide rail 14. The endless conveyor chain may be powered by suitable means (not shown) to provide a steady movement between the various stations along the belt.

55 In the embodiment shown, an additional tracking means or rail 16 is provided to carry the various trouser supporting units 17, one of which is illustrated in FIG. 1. As will be presently explained, portions of rail 16 form sidings extending along processing areas, and other portions are parallel to the rail 14.

60 Each unit 17 is carried by a hanger 21 which is tracked on the rail 16. Preferably the hangers 21 are of the swivel type whereby each unit 17 may be turned about its central vertical axis to facilitate loading and unloading operations. The particular hanger illustrated consists of a bracket 22 welded to unit 17 having an upper horizontal plate 23 formed with the groove 24. This groove serves to accommodate a pin 25 which in turn is attached to the lower end of the hanger rod 26. Rod 26 is carried by the hanger body 27 which in turn is provided with rollers 28 for tracking on the rail 16 (FIG. 3). Pins 30 extend laterally from the hanger

body 27. One of these pins is adapted to be engaged by a pick-up arm 29 secured to the chain 12. It will be evident that when a hanger 21 is being carried by a portion of rail 16 which extends parallel to rail 14, one of its pins 30 will be engaged by a pick-up arm 29, whereby the hanger and the unit 17 suspended from the same will be moved along with the conveyor chain 12. For siding portions of rail 16 which may extend along loading, unloading and processing areas, the hanger will remain stationary but may be moved manually to a position where it is engaged by the conveyor chain. While on a siding, the trouser supporting unit 17 may be manually rotated or indexed 180° about the axis of its hanger to facilitate access to both sides of the unit. The pin 30 of each unit is gravity urged into the associated groove 24 whereby detent means is formed tending to retain the unit 17 in a position parallel to the adjacent portion of the rail 16, but permitting manual rotation or 180° indexing as just described. In order to maintain unit 17 in a horizontal position without tipping, rod 26 is shown to extend through a plate 31 placed parallel to plate 23 and bolt 32 is threaded on rod 26 beneath plate 31.

The construction of each unit 17 will be described after an explanation of a typical plant layout (FIG. 4). However, it may be stated that each unit comprises a plurality of pairs of horizontal trouser supporting prongs, the prongs being preferably in two duplicate assemblies whereby garments may be applied or removed from both sides of the unit.

In the plant layout schematically illustrated in FIG. 4, line 41 represents the path followed by the conveyor chain 12, and is shown heavier than the lines 42 and 43. The latter represents sidings formed by portions of the rail 16. From the incoming conveyor portion 41a, each unit 17 may either continue along the conveyor portion 41b or be switched off the siding 42 or 43. Diversion of a unit onto one of these sidings is accomplished by conventional track switching means such as is well known in the art. After units leave the sidings 42 and 43, they are introduced back onto the main conveyor portion 41c, which picks up and then conveys the units into the conveyor portion 41d located within the curing oven 44.

For simplicity, in FIG. 4 a single conveyor chain 12 is indicated for feeding and picking up units from the siding and for moving the units through the oven 44. However, in practice it is more desirable to provide a plurality of separate conveyors each comprising an endless conveyor chain 12. For example, one such endless conveyor chain can be employed for feeding the sidings, another for receiving the units from the sidings, and a third for moving the units through the oven. With such an arrangement the various endless conveyor chains can be separately driven at suitable speeds to provide proper timing.

The garments to be processed have either been manufactured from resin impregnated fabrics or have been impregnated with a suitable resin containing impregnating material after the garments have been fabricated. The sidings 42 and 43 may pass in proximity with the pressing machines 46, 47 and 48. In the particular plant layout of FIG. 4, two sets of such pressing machines are shown to operate on garments removed from and reapplied to units on the two sidings 42 and 43. By way of example, as garments enter the siding 42, the pressing machine 48, known as a "topper" operates on the top portion of the trousers (i.e. the lowermost portions as the garments are suspended by the extremities of the pants legs). After the tops are pressed in the machine 48, the trousers are processed in the machines 46 and 47 known as "leggers," in which one pant leg is pressed in each machine. After the trousers have been pressed as just described, they are again loaded in the unit 17, and the unit advanced to the main conveyor portion 41c where it is picked up in the manner previously described and traversed to the curing oven.

The oven 44 may take any convenient form and may have any desired arrangement of conveyor path. The size of the oven should be such as to provide proper capacity and provide a proper curing temperature and holding period to effect the desired curing. In a typical instance, where the impregnating resin is of the urea formaldehyde type, the curing temperature may be of the order of from 250 to 400° F., with holding periods of the order of from 10 to 20 minutes. Specifically, 15 minutes at 340° F. has been found to be highly satisfactory.

After passing through the curing oven 44, the garments are conveyed to a suitable unloading station (not shown) where the garments are removed from the unit 17 and packaged for shipment. Here again the conveyor chain employed may be separate from that used to move the garments through the curing oven.

The preferred construction of the trouser supporting assembly unit 17 is illustrated in FIGS. 5-11. In this instance each unit consists of two duplicate assemblies 17a and 17b which are suitably attached side by side to the bracket 22 of the hanger 21. It will be evident that in place of using two duplicate assemblies, a single assembly may form a complete unit, and in such event the 180° indexing means may be omitted.

Each of the assemblies 17a, 17b consists of prong mounting means in the form of elongated base members 56 and 57 (FIGS. 7 and 8). The members 56 of both assemblies are attached to the bracket 22. These members may conveniently be in the form of angle irons with overlapping flanges 58 and 59, and preferably are retained together for limiting sliding movement. Thus the ends of member 57 (FIG. 8) are shown provided with portions 61 and 62 which underlie the slots 63 and 64 in the overlying member 56. Bolts 66 and 67 are applied in the manner illustrated and serve to loosely retain the parts together whereby members 56 and 57 may be adjusted with respect to each other in the direction of their length. In addition, bolts 65 (FIG. 7) are shown as supplementing bolts 66 and 67 in retaining members 56 and 57 together. The members 56 and 57 are urged in opposite directions by the compression spring 68. One end of this spring seats upon portion 69 of member 56 and is retained in place by a screw or like member 71, and the other end seats upon the corresponding end portion 75 of member 56. Screw 71 may be manually adjusted to limit movement of member 57. A manually adjustable screw 72 has threaded engagement with portion 73 of member 56 and its end abuts the adjacent end portion 74 of member 57. It will be evident that by adjusting the setting of screws 71 and 72, the members 56 and 57 can be adjusted longitudinally with respect to each other and fixed in place to prevent relative movement. When screws 71 and 72 abut ends 74 and 75 of member 57, there is no relative movement between members 56 and 57 and spring 68 becomes unnecessary. As will be presently explained, this permits adjustment of the spacing between the prongs.

A plurality of pairs of prongs are attached to the members 56 and 57 and extend horizontally for supporting the garments. The prongs 76 and 77 of each pair are attached to the members 56 and 57 respectively. Thus the base portion 78 of prong 76 is shown attached as by means of bolts 79 to the member 56 (FIG. 9). Similarly, the base portion 81 of each prong 77 is attached as by means of bolts 82 to the member 57. The prongs themselves may be either integral with the base portions 78 and 81, or may be made separately and attached to the base portions as by means of attaching screws 83.

The trouser engaging portions 86 and 87 of the prongs may vary in details of construction, but in general they should provide parallel portions of predetermined spacing between which the trousers or other garments are engaged. In the particular construction illustrated in FIGS. 5, 6 and 10, the portions 86 and 87 have a configuration in cross section corresponding to an inverted V, thus providing upwardly divergent side portions 88, and lower

edge portions or margins 89. The edge portions 89 of each pair have a predetermined spacing (FIG. 5) for receiving the garment, and assuming that the garment is to be conventional trousers, the portions 89 are notched as indicated at 90 to accommodate the side seams.

In normal operation the spacing between the prongs is set in accordance with the character of the garment to be processed. In general the spacing should be of insufficient width to pass the cuff of the garment. However, it should be sufficient to pass the seam of a pant leg, and should bear a predetermined relationship to the overall thickness of the cloth forming the leg.

The spacing between the lower margins of the prongs should be such that the garment is secured during passage through the oven yet no heavy marking of the uncured garments occurs. If the spacing is too wide, the cuff will pass through. If the spacing is too narrow, permanent creases or marks will be formed on the pant leg along the lines of engagement with the prongs. Conventional pants hangers exert spring pressure which leaves marks on uncured garments. By the arrangement herein described, no positive pressure is exerted on the garment beyond the weight of the garment itself and this pressure is confined to a narrow area adjacent the bottom of the plant leg.

Since the prongs support the inverted trousers beneath the cuffs (or thickened terminal portions or hems on cuffless trousers) and notches are provided to accommodate the side seams, the pant leg, along the line where it is supported, consists of two thicknesses of cloth. Consequently the spacing between prongs of each pair must be slightly more than two thicknesses of the cloth from which the garment is made to permit the pant leg to slide in and out. On the other hand, with certain cuffless trousers the spacing cannot be equal to four thicknesses of cloth since the terminal hem of the pant leg is only four thicknesses of cloth and the garment would fall through the prongs.

Accordingly, a spacing between the prongs which is more than two thicknesses of the cloth from which the garment is made and less than four thicknesses is sufficient to suspend the pant leg. In practice, at least 2 mils (0.002 inch) more than two cloth thicknesses is generally required to permit entry and removal of the pant leg in the pairs of prongs. Similarly, at least 10 mils (0.01 inch) less than four cloth thicknesses is usually necessary to hold the pant leg from falling through the prong space when the unit is in motion. Expressed as a formula with X being the thickness of the cloth from which the garment is made, the prong spacing (S) should be:

$$S \geq 2X + 0.002 \text{ inch}$$

$$S \leq 4X - 0.01 \text{ inch}$$

Preferably the prong spacing should not exceed three cloth thicknesses so that gripping of the pant leg is secure but still without leaving a mark. The range of about $2X + 0.01$ inch to $3X$ is preferred to give best gripping with no permanent marking. Any conventional measuring device may be used for measuring cloth thickness, such as the Ames Thickness Measure available through Cutters Exchange, Inc., Nashville, Tenn.

It will be evident that the spacing between the prongs may be set for garments having comparable cloth thicknesses. However, where the cloth thickness varies considerably, as for example with relatively heavy corduroy cloth, the spacing between the prongs must be adjusted accordingly. This adjustment can readily be made by turning the screws 71 and 72 at the ends of the supporting unit. We have found in practice that a maximum spacing between the prongs of 250 mils is generally adequate for all of the more common types of cloth from which trousers are made although some corduroys may require greater spacing. To make a proper adjustment, the prongs are adjusted to provide a spacing less than four thicknesses of

the cloth and more than twice the cloth thickness plus two mils.

Due to the cantilever support in prongs 76 and 77 at portions 78 and 81, a very small amount of "give" or flexibility is present at the open ends of the prongs for easy insertion of the pant leg. Since prongs 76 and 77 are rigid, the prongs do not spread to the extent that the pant leg falls through. Nevertheless, the added thickness of the side seam can easily be introduced into notches 90 by virtue of the cantilever support. The compressibility of the fabric layers exceeds the give in the prongs to further facilitate entry of the pant leg.

The prongs 76, 77 should be of sufficient length so that each pant leg is engaged along its entire width. In general the prongs have a minimum area of contact with the cloth, and no single point along the prongs has a substantially greater contact pressure than the other parts. The fact that each pair of prongs holds a single pant leg permits each leg to be separate from the other so that there is no physical contact between them during curing, and there is no contact between the legs of adjacent garments. The portions 88, being upwardly divergent, maintain the cuffs vertical without physical contact. In the curing oven, hot air is generally circulated with sufficient velocity to effect some movement of the garments. Here again support of the pant legs by the prongs is such that movement of the garments because of air currents in the curing oven does not cause physical contacts such as might cause undesirable markings.

In FIG. 6, two pant legs 91 are shown engaged with adjacent pairs of prongs. It will be seen that the two legs are normally spaced apart to prevent direct physical contact. FIG. 10 illustrates how the prongs of each pair can be adjusted toward and away from each other to vary the spacing between the same. A minimum adjusted position is indicated in dotted lines.

As explained above, adjustment between the prongs is desirable to adapt the apparatus to various thickness of cloth. Where the garments being handled are made of comparable weight cloth, the prongs may be affixed to a support member and the adjustment described above may be omitted. Thus as shown in FIG. 11, the base portions 92 of the prongs 93 and 94 are secured as by bolts 96 and 97 to the support member 98. Assuming that two assemblies are to be used to form one supporting unit, a common member 98 for both assemblies may be used as shown in FIG. 11. Member 98 may be attached to bracket 22 of the hanger 21 (FIG. 5) as by bolts (not shown).

To summarize operation of the apparatus described above, the trousers impregnated with synthetic resin are loaded onto the supporting units 17 by placing one pant leg between each pair of prongs 86 and 87. The conveying means moves a unit 17 to one of the available sidings 42 or 43 for pressing. Upon entry to a siding (e.g., siding 42) the trousers are pressed in the pressing machine 48. Thereafter the legs of the trousers are pressed in machines 46 and 47, one leg being pressed in each machine. After pressing, the garments are again suspended on unit 17, and this unit moved for engagement with the conveyor portion 41c. Thereafter the garments enter the curing oven 44 to effect curing to a point where further pressing of the garments is not necessary. After passing through the curing oven, the garments may pass to a labelling station where appropriate labels are applied, and thence to an unloading station where the garments are unloaded, inspected and packaged.

Since curing temperatures employed in the curing oven are of the order of 250 to 400° F., care should be taken to use such materials in the construction of the conveying means and the supporting units as will not be subject to deterioration. In practice it has been found satisfactory to construct the prongs of die cast aluminum. The opposed exterior faces of edge portions 89 should be suitably finished to present smooth surfaces to the garments. If desired, the prongs may be coated with suitable materials,

such as Teflon. Such coating materials should be compatible with the curing temperature employed.

The single spring 68 of the apparatus described above is preferably of stainless steel to withstand repeated heating in the curing oven 44. Conventional spring steel tends to be tempered and fail after relatively short periods in the repeated heating and cooling cycle. For this reason, springs are avoided in the apparatus described except for spring 68. Spring 68 does not exert any substantial pressure on any given pant leg because of the frictional engagement of the members 56 and 57. In fact, spring 68 is unnecessary when both end screws 71 and 72 abut member 57 at ends 75 and 74, respectively (FIG. 8). Spring 68 only serves to keep members 56 and 57 from sliding when either screw 71 or 72 has been loosened. Thus, the pressure exerted on each pant leg is only about half the weight of the garment itself, since positive spring pressure is absent.

The apparatus described above employs one pair of prongs for each pant leg. While this is preferred it will be evident that with the embodiment illustrated in FIG. 11, the spacing between the prongs may be such that a single prong may be interposed between the two pant legs. In other words, only three prongs may be employed for two pant legs.

It will be evident from the foregoing that I have provided apparatus which has a number of desirable features as applied to the permanent-press treatment of garments. The novel trouser supporting units enable the trousers to be readily loaded and unloaded to facilitate automated operations at various stations for quantity plant production. The construction is such that only the desired creases will be made permanent and all undesirable wrinkles, folds, markings, etc., are avoided.

I claim:

1. In a garment curing apparatus including an oven, means for supporting a plurality of pairs of resin-imregnated trousers for curing in the oven comprising a first and second cooperating base members, a plurality of pairs of rigid prongs, alternate prongs of each pair being attached to the first member and remaining prongs being attached to the second base member, the prongs of each

pair being parallel and spaced apart such that marking of the garment upon curing is avoided, and means for adjusting said cooperating base members relative to each other to adjust the spacing between the prongs of each pair.

5 2. A garment curing apparatus as in claim 1 wherein said adjustment means consists of a single adjustable member cooperating with said base members which is adjusted manually to control the spacing between the prongs of all of said pairs.

10 3. Garment curing apparatus as in claim 1 wherein said first and second base members are elongated and disposed in adjacent parallel relationship and in which said prongs extend substantially at right angles to said base members.
